UNITED STATES PATENT OFFICE.

ROBERT DAVIDSON MELROSE, OF EDINBURGH, SCOTLAND.

NEEDLE-THREADER.

SPECIFICATION forming part of Letters Patent No. 778,985, dated January 3, 1905.

Application filed April 28, 1904. Serial No. 205,407.

To all whom it may concern:

Be it known that I, ROBERT DAVIDSON MELROSE, machinist, a subject of the King of Great Britain, and a resident of 12 Atholl Place, 5 Edinburgh, Scotland, have invented certain new and useful Improvements in Needle-Threaders, of which the following is a specification.

My invention relates to needle-threaders, 10 and in its preferred embodiment comprises a casing and a reciprocating thread plunger or carrier and means whereby the thread and needle-eyes may be held in register with the said carrier, whereby the thread may be engaged, projected through the eye of the 15 needle and into position to be engaged by the hand of the operator during a single reciprocation of said carrier.

My invention differs from the devices of 20 the prior art in having a projecting carrier engaging the thread to push the same through the needle-eyes instead of drawing the thread through by means of hooks. This difference of structure and operation not only greatly 25 simplifies the manufacture of the device, but also simplifies the operation thereof. In devices of the prior art where the thread is drawn through the eye of the needle by means of hooks or clamps it is essential in the first 30 operation to insert the hook through the needle-eye, to grasp the thread, and then draw the engaged thread and hook or eye backwardly through the needle, so that the operator may grasp the thread by the fingers.

35 By the employment of my improved device one of the two complete operations in the process of threading the needle heretofore necessary is entirely avoided. The reciprocating thread-projector first engages the 40 thread and then projects the same through the eye of the needle and into a position to be grasped by the hand during the reciprocation of the plunger from one limit of its movement to the other, the said plunger being restored 45 to a normal position by automatic means hereinafter described. In the preferred construction I also provide means whereby the thread is held in a position to be engaged by the projector and means whereby the eye 50 ends of the needles may also be held in a plane

of operation of said projector, thereby avoiding the necessity of the operator's having to carefully adjust the needle and thread in position.

My invention also preferably includes a 55 composite structure having a thread-container, which latter is provided with a thread-cutter, enabling the operator to sever a desired length of thread without the employment of scissors or other cutting means. 60

My invention will be described more fully with reference to the accompanying drawings and will be pointed out more particularly in the appended claims.

Figure 1 is a side elevation of the application. Fig. 2 is a cross-section on the line X X, Fig. 1. Fig. 3 is an enlarged view of the pusher or spear in side elevation. Fig. 4 is a plan view of the spear or pusher. Fig. 5 is a side elevation of the spear or pusher with 70 its spring. Fig. 6 is a view drawn to an enlarged scale, showing the method of threading a needle. Fig. 7 is a front end view, Fig. 8 a longitudinal section, and Fig. 9 a back end view, of the needle-block. Fig. 10 is a section 75 of the needle-block on the line Y Y, Fig. 8. Fig. 11 is a horizontal cross-section through the center of the needle-block Fig. 8. Fig. 12 is a side view of the needle-block. The views of the needle-block Figs. 7 to 12 are 80 drawn to twice the size of the needle-block Fig. 1. Fig. 13 is an enlarged view of the end of the thread-holder.

On the drawings the same reference-letters wherever repeated indicate the same parts. 85

It will be seen that the appliance consists of a casing *a*, made of thin metal or other suitable material and having at the one side of it a small tubular casing *b*, which serves for holding needles, and a second similar casing *c* 90 for holding thread. The needle-case *b* is provided with a cover *b'*, while the thread-case *c* is provided with a cover *c'*. The cover *c'* may have, as shown at Fig. 13, cross-cuts or converging slits *c''* in its end, through which the thread can be drawn. If desired, the cuts may be of star or other shape, and they are for the purpose of catching the thread after it has been pulled out of the case *c* and broken off so as to leave a portion projecting. The 95 100

cuts are sufficiently narrow to hold the thread with a certain amount of frictional grip.

Arranged within the casing *a* is the plunger *d*, which has a thickened end *e* and a stop or shoulder *f*. The thread-engaging end of the plunger is preferably flat at *g* to constitute a thread carrier or projector, and at the opposite end an eye or ring *h* is provided, by means of which the appliance can be attached to the 10 wearing-apparel or to a bag, work-basket, or the like. Coöoperating with the plunger is a spiral spring *i*, which bears against the shoulder *f* at one end and against the needle-block *j* at the other end. The rear end of the shoulder 15 when the plunger is in position within the casing *a* bears against a flange at the interior of the rear end of the casing, so that the plunger cannot work or be pulled out of the casing.

The carrier or projector is made thin and 20 narrow, so as to pass through the eye of a needle easily, and has at each side of it a longitudinal groove *k*, and its extreme end may be U-shaped, as at *l*, or may be otherwise recessed or be square cut. The recess catches 25 the thread and projects or carries it through the eye of the needle, while the longitudinal grooves serve as guideways for the looped thread. The projector may be made parallel throughout its length or may be slightly tapered. 30

The needle-block may be made of metal, glass, or other suitable material and in a single piece or two or more pieces secured together. In this block is a longitudinal passage-way *m*, in which the carrier works, and the shape of this passage-way corresponds with the shape of the carrier. It is or may be made round or oval for the first part of its length, and then it is narrowed down so as to 35 form a narrow vertical slot or channel which just admits of the free passage of the projector. Two longitudinal thread guides or grooves *n* are made in the passage, one at each side, and these grooves serve, in correlation with the 40 grooves *k* in the carrier, as channels along which the thread can freely travel as it is being pushed through the eye of the needle. 45

The thread is presented to the projector through a vertical slit *o*, made in the needle-block and extending from the top of the block down to the center of the passage *m*, as shown in Fig. 8, and this slit is only wide enough to admit a thread of a thickness suitable for entering the eye of the needle. Formed vertically in the needle-block from the top down to slightly below the passage *m* are two (or other number) of holes *p p'* for the reception of the eye end of the needle to be threaded. If there are two holes, as shown at Fig. 8, 50 then one is of a slightly-larger diameter than the other, so as to admit a larger size of needle. Thus the hole *p'* is larger than *p*. Of course there might be a number of different-sized holes; but generally two will be sufficient. 55

The appliance may be shaken slightly when the needle is inserted in the hole, so as to aid in the proper presentation.

The front end of the needle-block is cut away or beveled at each side, as shown at *q q'*, Fig. 7, 60 in order to facilitate the grasping of the thread with the finger and thumb.

The needle-block is preferably removably fitted in the end of the casing by a screw *r*.

s designates a dust-cover, which is or may be 65 connected to the holder *c* by an ornamental chain *t*. This cover serves to cover over the needle-block when the appliance is not in use, and thereby prevent dust or dirt gaining access to the hole or holes and passage and 70 thread-guide in the block.

If desired, the appliance may be made without the holders *b c*, and in this case the plunger may be made hollow, so as to serve as a receptacle for needles and (or) thread. 75

When threading a needle, the eye end thereof is inserted into the proper hole *p* or *p'* in the needle-block, and, if necessary, it may be shaken slightly, so as to facilitate the proper presentation of the eye of the needle to the 80 carrier. The thread is passed or drawn down the slit *o* to the bottom thereof, and then the projector is thrust forward, so that its end *l* catches the thread and projects it through the eye of the needle, as at Fig. 6, (where *v* is the 85 needle and *w* the thread.) When the pressure on the plunger is relieved, the spring *i* retracts the plunger and withdraws the projector from the needle-eye, at the same time leaving the looped thread *w* in the eye and projecting out 90 at the front of the block, so that it can readily be caught between the thumb and finger and the one end of the thread pulled completely through the needle-eye, whereupon the needle, with its thread, can be raised up out of 95 the block. 100

Of course, if so desired, the thread can be inserted in the slit *o* before the needle is inserted in its hole *p*.

Having now fully described my invention, 110 what I claim, and desire to secure by Letters Patent, is—

1. A needle-threader, including a casing provided with an axial passage having a reduced portion at one end, and a thread-carrier located in said passage and having a reduced end, the walls of the reduced end of said passage engaging the reduced end of said thread-carrier and guiding said carrier in a prescribed position, and causing the same to register with a thread-slit and needle-hole intersecting the reduced portion of said passage. 115

2. A needle-threader, including a casing provided with an axial passage having a reduced portion at one end, a thread-carrier located in said passage and having a reduced end, the walls of said reduced portion of the passage engaging the reduced end of said carrier and guiding the same in a prescribed po- 120 125 130

sition and causing the same to register with a thread-slit and needle-receiver intersecting the reduced portion of said passage.

3. A needle-threader, including a casing 5 provided with an axial passage having a reduced portion at one end, the walls of said reduced portion of the passage being provided with longitudinal grooves, and a thread-carrier located in said passage and having 10 a reduced end provided with longitudinal grooves adapted to register with the grooves in said passage, the walls of said reduced portion engaging the reduced end of the carrier

and guiding the same in a prescribed position to bring said grooves of the carrier and 15 passage in register, and causing said carrier to register with a thread-slit and a needle-hole intersecting the reduced or grooved portion of said passage.

Signed at Edinburgh, Scotland, this 13th 20 day of April, 1904.

ROBERT DAVIDSON MELROSE. [L. s.]
